CHAPLET

George H. Angell, Cleveland, and Harvey F. Lorenz, Cleveland Heights, Ohio, assignors to Angell Nail & Chaplet Company, Cuyahoga Heights, Ohio, a corporation of Ohio

Application May 6, 1935, Serial No. 19,974

8 Claims. (Cl. 22—184)

This invention relates to chaplets such as are used in metal foundries for the purpose of positioning the core in a mold. More specifically, the invention is directed to comparatively heavy chaplets for use where the metal is to be cast with considerable thickness of wall.

The objects of the invention are to provide such a chaplet which will very effectively position the core, supporting its weight and preventing its flotation in the molten metal until the metal has solidified, but on the other hand is so arranged that the stem of the chaplet will effectively fuse with the metal and make a perfectly tight engagement while the supporting action is still effective.

Our chaplet is illustrated in the drawing hereof, is hereinafter more fully described, and its essential novel characteristics are summarized in the claims.

20 The drawing illustrates our invention embodied in a chaplet of the double-headed type. Fig. 1 is a side elevation of such chaplet; Fig. 2 is a plan thereof; Fig. 3 is a longitudinal central section, as indicated by the line 3—3 in Fig. 2; Figs. 4 and 5 are cross-sections on the correspondingly numbered lines on Fig. 1.

In each of the views, 10 indicates the chaplet post or stem and 20 each of the two heads abutting the ends of the stem and preferably 30 homogeneously united therewith. These heads are preferably flat members of any desired contour, being shown as square. The stem 10 is cylindrical where it joins the heads, as indicated at 11. At the central region, the stem is provided with a radially extending annular web 12. In the region between the annular web and the cylindrical portion, the exterior of the stem is fluted at 13, the flutes as shown being inclined. The flutes on one side of the central rib 35 incline in one direction and those on the other side in the other direction, in herringbone fashion, as clearly shown in Fig. 1.

It results from the fluting that a cross-section through the stem in any region between the 40 central-rib and the cylindrical portion presents the contour of a conventional star, as indicated by the cross-sectional views Figs. 4 and 5.

The chaplet may be readily made by thread-rolling the stem and thereafter fastening the 45 head plates to opposite ends of the stem. This may be done by riveting, but is preferably accomplished by a welding operation, to form thereby a homogeneous unit. In some instances the stem will be provided with only one head.

50 After the head or heads have been applied to

the formed stem the unit is complete, though if desired it may thereafter be covered with a readily fusible metal which is a rust-preventer, as, for instance, tin or copper.

It will be seen that when the chaplet described 5 is used in metal founding, the molten metal as it surrounds the stem will result in the fusing of the edges of the annular rib 12 and the ridges of the flutes 13, thus making a very tight, homogeneous connection without melting the general 10 body of the stem, so that the support of the core remains effective.

The flutings, which come to rather sharp 15 ridges at their edges as illustrated in Figs. 4 and 5, result in the melting of the ridge portions so that a very homogeneous connection is made 20 with the metal. Should there be any passageway in the metal adjacent the remaining stem, this is interrupted by the annular rib 12, which 25 reduces the chance of any such passageway resulting in the finished product. By making the annular ribs inclined, they engage different annular regions of the metal and reduce the chance of a bubble in the metal producing a blister at any flute. That is to say, if the rib should not 30 effectively engage the metal at some region, it will at some other portion of the rib.

By making the ribs in the herringbone fashion there is no possibility of the stem, even if it 35 becomes separated from the heads, acting like a screw in the casting, and this herringbone arrangement of the flutes also enables more ready thread-rolling of the stem. The herringbone arrangement of the ribs also imparts a whirling 40 action to the molten metal directing the metal against both the heads and the annular rib.

In the chaplet illustrated, the spiral ribs terminate a short distance from the ends at the 45 head of the chaplet, leaving the stems cylindrical and of less diameter than the exterior of the fluted portion immediately adjacent the heads. This allows that portion of the molten metal which is directed by the ribs toward the heads to build up effectively at the head and in close union with the stem at the ends of the ribs, and it is believed that this acts somewhat, as a limit to further movement of metal toward the head, insuring the same compacting in the flutes leading toward the head.

50 Experience with our chaplet in actual casting operations and tests of the resulting product demonstrates that the chaplet effectively holds the core and very intimately unites with the cast metal, as desired.

We claim:

1. A solid chaplet stem adapted to carry a head on one end thereof, the stem being fluted, and provided with a transversely extending annular rib 5 interrupting said flutings and extending outwardly beyond the outer ridges of said flutes.
2. A chaplet stem, flutings on the exterior of the stem extending in herringbone fashion from an intermediate region of the stem.
- 10 3. A chaplet stem comprising a central shaft, adapted to have a pair of heads homogeneously connected to the opposite ends of the stem and V-shaped flutings on the exterior of the stem extending in herringbone fashion from a central 15 region of the stem.
4. A chaplet stem comprising a central shaft and adapted to carry a pair of plate-like heads on opposite ends of the stem, the stem having a central wafer-shaped projecting rib and having helical 20 flutings formed in the rib and inclining oppositely on opposite sides of the rib, said flutings terminating at their outer extremities in relatively sharp ridges, the stem being cylindrical beyond the ends of the flutings and adjacent the heads.
- 25 5. A chaplet stem comprising a shaft-like member, an annular wafer-shaped rib surrounding said shaft adjacent the mid-point of its length, flutings positioned on said shaft in herring-bone fashion with the apex of said herring-bone adjacent the annular rib and said flutings having substantially V-shaped cross sections terminat-

ing in relatively sharp outer edges, and a substantially cylindrical portion extending beyond said fluting to the shaft end of less diameter than the outer extremities of such fluting.

6. A chaplet stem, comprising a central shaft and adapted to carry a head on an end thereof, a central wafer-shaped projecting rib carried on the stem and spiral flutings formed in the stem and inclining oppositely on opposite sides of the rib. 5

7. A chaplet stem comprising a shaft-like member, an annular wafer-shaped rib surrounding said shaft adjacent its mid-region, fluting positioned on said shaft on one side of said rib and merging with said rib and extending in helicoidal 15 fashion to a region adjacent one end of said stem, said fluting having substantially V-shaped cross-sections.

8. A chaplet stem, comprising a central shaft and adapted to carry a pair of heads on opposite 20 ends of the stem, said stem comprising an annular wafer-shaped rib between the two ends of said stem, helical fluting extending from said rib toward one end of said stem, said fluting terminating at its outer extremities in relatively sharp 25 ridges and a substantially cylindrical portion of said stem extending beyond said fluting to the shaft end.
